TIE RACK OR SIMILAR ARTICLE

Frank Morrow, Johnston, R. I., assignor to Frank Morrow Company, Providence, R. I., a corporation of Rhode Island

Application November 26, 1957, Serial No. 48,668

Term of patent 7 years

(Cl. D33—8)

Fig. 1 is a front elevational view of a tie rack or similar article embodying the instant design;

Fig. 2 is a plan view thereof;

Fig. 3 is a rear view thereof;

Fig. 4 is an end view thereof; and

Fig. 5 is a fragmentary perspective, on an enlarged scale, showing the ornamental blankings.

The ornamental blankings shown in Fig. 5 are schematically shown in Figs. 1 and 2 and extend the entire length of the spiral member.

I claim:

The ornamental design for a tie rack or similar article, substantially as shown and described.
